UNITED STATES PATENT OFFICE

PATRICK P. LA MONTAGNE, OF KANKAKEE, ILLINOIS, ASSIGNOR TO PARAMOUNT TEXTILE MACHINERY COMPANY, OF KANKAKEE, ILLINOIS, A CORPORATION OF ILLINOIS

KNITTING MACHINE

Application filed March 23, 1928. Serial No. 264,030.

This invention relates primarily to knitting machines and, more especially, to a knitting machine adapted automatically to knit a complete ribbed-leg stocking from beginning to end and in which the knitting commences at the toe-end.

My present concept involves an improvement on and a carrying forward of certain subject-matter disclosed in United States Patent No. 1,282,880, dated October 29, 1918, on the invention of myself and Peter Gable, entitled Knitting machines.

A feature of the machine revealed in that patent resides in producing a proper finish to the top of the stocking and embodying therein an anti-ravel—that is, an anti-run-back—course and, also, a section of work designed to ravel out and form a distinctive line of demarkation; this result being effected, in part, by controlling the operation of the needles of the machine in a unique manner.

The operation of that machine, as disclosed in the patent, has, at times, been attended with certain difficulties which it is the object of the present invention to obviate: In other words, when the anti-runback course of the stocking has been knit therein and certain of the knitting instrumentalities are resuming normal position, there is a tendency of some of the needles of the machine to cut the fabric. This is due to the fact that—after the cylinder has been lowered for the knitting of the lock-stitch (fully disclosed in said patent) and at which time the cylinder-needles are below their normal knitting position and feeding yarn to the dial-needles while not casting off their previous stitches (it being understood that the dial-needles are, at that time, knitting normally while the cylinder-needles retain their respective previous stitches)—on raising the cylinder to resume normal knitting, a cutting of the fabric is quite apt to be effected by one or more of the group of cylinder-needles which would, at the moment, be under the cylinder-stitch-cam at the time of the raising of the cylinder to normal knitting position: In changing the cylinder-height from the lock-stitch level to the normal knitting level, there is a point

at which the needles will draw such a tight stitch as to cause the aforementioned cutting thereof by the needles, because the tension or tightness of the fabric produced in a machine of this type is (as well understood) regulated by the relative position of the cylinder; that is, the fabric is loosened by the raising of the cylinder and tightened by lowering it. The extreme tight-tension cylinder-height is passed when the cylinder is actuated from its lock-stitch level to its normal knitting level. The cutting is caused by the failure of the needles, at that particular stage of the operation, to draw enough yarn to form a stitch. There is a point, at this stage of the operation, where the needles neither draw sufficient yarn to form a stitch, nor remain out of action. In fact, only enough yarn is drawn by the needles to just cast off. In consequence, when one of the needles starts to raise up through the stitch, it will (because of its size) be of too great diametral dimension for the amount of yarn formed around its hook and, as its cheek is larger than the stitch itself, it severs the latter.

I have discovered, and my present invention is predicated upon the discovery, that by providing means for temporarily actuating and maintaining selected needles out of position to take yarn at a predetermined time, they cannot, then, form a stitch, but will retain their previous stitches, the yarn which has been fed to them lying, then, in front of the needle. In other words, my concept involves the provision of means for maintaining certain of the knitting instrumentalities in a predetermined but unusual relation, whereby those cylinder-needles which would ordinarily cut the fabric are temporarily maintained out of action so that, during one course, they will not take yarn.

In the accompanying drawings, constituting a part of the present disclosure, I have illustrated a preferred embodiment of my concept; but it is to be understood that these drawings are merely illustrative, that other embodiments and utilizations are within the spirit of the concept, and that the particular embodiment revealed is susceptible of a wide range of modification and variation without

sacrificing any of the salient features and underlying principles of my invention.

In these drawings:

Figure 1 is a fragmentary view, in elevation, of the machine typified in the aforementioned patent and with my present invention incorporated therein;

Fig. 2 is a view in vertical transverse section thereof, taken on the line 2—2, Fig. 3; 10 Fig. 3 is a view in horizontal section of the bed-plate of the machine and of the associated parts thereof, taken on the line 3—3 of Fig. 2;

Fig. 4 is a view in perspective of certain of 15 the instrumentalities—in the form of a needle-camming device—which control the position of a special set of needles for a non-cutting operation; and

Fig. 5 is a fragmentary view of a portion 20 of a string of stockings, particularly illustrating (more or less diagrammatically) the section thereof wherein tuck-knitting, anti-runback course, etc., are formed.

Inasmuch as the machine, in general, with 25 which my needle-controlling device is associated is fully disclosed in the aforementioned Patent No. 1,282,880, a detailed description thereof is deemed unnecessary. It will, therefore, suffice to outline it as follows:

30 Operatively associated with a bed-plate 1 is a needle-cylinder 2 movably mounted in relation to the bed-plate; a cylinder cam-carrying ring 3 is rotatably mounted on the bed-plate; a cylinder-stitch-cam 4 is operatively 35 mounted on this ring; a sinker-cam ring 5 is rotatably mounted on the upper portion of the cylinder; a dial 6 is mounted within the upper portion of the cylinder; and a set of dial-needles 7 is disposed in the dial.

40 The cylinder 2, in this instance, is provided with the usual sets of long-butt and short-butt cylinder-needles 8 and 9, respectively; and, in addition, it mounts a special set or auxiliary set of cylinder-needles 10, these being 45 special in the sense that they function differently from the other sets (as will hereinafter be more fully described) and have relatively longer butts to facilitate their functioning.

50 Appropriate means are, as disclosed in said patent, provided for operating the usual instrumentalities of the machine in the customary way for effecting plain-knitting, rib-knitting, etc., and including means for raising and lowering the cylinder to vary its knitting action, in the well-known manner.

55 Preferably and as shown, means are, in the present structure, also provided for controlling the operation of the special set of needles 10: These means (herein referred to as a needle-controlling device) include a cam-carrying member—in this instance in the form of a bracket 11—movably mounted on the usual gear-ring 11^a and rotating on a 60 pivot 11^b. The bracket mounts a cam-piece

12 which is adjustably mounted, as by means of a slot-and-screw attachment (not shown) on the bracket. Threaded into the bracket is a headed-member, in the form of a screw 13, adapted for adjustment therein, and held in any of its adjustable positions by a binding-element 14 through which the screw 13 is threaded and which, itself, is held by a screw 15 extending into the bracket. Threaded through the bracket, adjacent its outer extremity, is a limit-stop, in the form of a screw 16, which (like the screw 13) is held in any of its adjustable positions by a binding-element 17 carried by a screw 18 also threaded into the bracket. Carried by the bracket, adjacent its pivot, is a screw 19 to which is secured one end of a bracket-returning spring 20, the other end being secured to an attaching element 21.

Depending from the sinker-cam-ring 5 is 85 a member-operating member, in the form of a spring-finger 22, provided at its lower extremity with a cam-surface 23 which, during the lowering of the cylinder, strikes the screw 13 on the cam-bracket 11, which action 90 swings the bracket on its pivot and toward the cylinder-needles and, thus, in position to dispose the cam-piece 12 for engagement with the butts on the special set of needles 10. The finger 22 is preferably more or less 95 resilient so that its engagement with the headed-member on the bracket will provide for any irregularity in the parts, and insure engagement of the stop-screw with the cam-carrying ring 3. The adjustability of the screw 13 insures engagement of the finger therewith. The adjustability of the screw 16, which abuts against the periphery of the cylinder-cam-ring 3, provides for varying the 100 extent of movement of the bracket and, thus, insures the proper positioning of the cam-piece in relation to the path of travel of the engageable butts of the special needles. 105

When the cylinder is raised to return it to normal position, the spring-finger 22 will be disengaged from the screw 13, whereupon the bracket-returning spring 20 will effect an outward swinging of the bracket on its pivot, and, thus, return the bracket to normal position, and thereby the cam-piece is disposed out of the path of engagement of the butts of the special needles. 110

115 In Fig. 5, I have illustrated a portion of a string of stockings which, in the order of knitting the same, comprises a looper selvage *g*, a toe-portion *h*, a so-called ring-toe-portion *i*, a ribbed instep and sole section *j*, a heel-portion *k*, an ankle-portion *l*, a plain ribbed section *a*, a tucked welt *b*, a second plain ribbed section *c*, an anti-run-back 120 course *d*, a break *e* in the anti-run-back course, and a run-back section *f*. 125

Operation

130 The operation of the machine, and in par-

ticular of the device just described, will now be more or less apparent.

At the end of the ribbed work *a*, through the operation of the machine as described in the aforementioned patent, the dial-needles will have been brought into a position such that they take the yarn at each course but cast off only at every other course, thus making the welt *b* composed of tucked stitches, all as described at length in said patent. Then, the dial-needles are restored to position for knitting the plain ribbed work *c* which, it is to be understood, forms no part of the finished stocking. Then, the cylinder is lowered for knitting the lock-stitch or anti-runback course *d*. The cylinder remains in this lowered position during one course of knitting, and, during this course, the cylinder-needles pull down the yarn to the dial-needles; the latter knitting stitches, and the cylinder-needles not knitting stitches. There is thus formed a course of lock stitches which prevent the raveling back of the web, as set forth in said patent.

25 The cylinder is thereupon restored to position for knitting ribbed work, and several courses of this work are then knitted to present a narrow zone or strip which runs back or ravel to the so-called lock-stitch *d*, thereby forming the runback section *f* which, as the knitting continues, will be raveled out by the natural tension placed upon the web and, thus, indicate clearly on the web the line at which the string of stockings should be cut apart. It is during the stage of restoring the cylinder to its normal knitting position that the cutting action of the needles usually occurs—at point *e*—and at which point the device for preventing the needles cutting effects its function. The anti-runback course is, therefore, not a complete round but is interrupted at the point *e* when the butts of the needles 10 are engaged by the cam-piece 12.

As already described, the lowering of the cylinder positions the spring-finger 22 in engagement with and effects an inward swinging of the cam-bracket 11 to position the cam-piece 12 into the path of the butts of the special set of cylinder-needles 10; but the stop-screw 16, by its engagement with the periphery of the cylinder-cam-ring 3, prevents the cam-piece from being positioned in the path of the butts of the main sets of needles 8 and 9; hence, the cam-piece does not become effective on these needles. The cam-piece is selectively effective, therefore, only on the special needles, and positions and maintains these at a higher point than the normal high-point movement of the main needles. Hence, these special needles 10 will, then, be above a yarn-taking plane, the yarn which would ordinarily be supplied thereto lying in front of those needles.

At the conclusion of the knitting of the course of lock-stitches *d*, the various instru-

mentalities are restored to normal position; and, during this operation, the cylinder will have been raised to its normal position and, simultaneously therewith, the spring-finger 22 is disengaged from the cam-carrying-bracket which, then, under the action of the spring 20 is restored to its normal position. The parts are then in position for the knitting of plain ribbing which runs or ravel back and forms the open-work section *f*. At 75 the completion of this section, the dial-needles cast off their stitches and are thrown out of action, and the various knitting instrumentalities are positioned to commence knitting the foot-portion of the next stocking, comprising the looper-salvage *g*, the toe-portion *h*, the ring-toe *i*, the sole and instep portion *j*, the heel-portion *k*, the ankle *l*, and back to plain ribbing *a*, and the cycle of operations for the knitting of another complete 85 stocking continues.

It is to be noted that there are a relatively few of the special needles 10, usually not more than half a dozen, the number varying according to conditions. These needles are, preferably and as shown, juxtaposed to each other in their respective slots in the cylinder so that there is a row or group of these, the space occupied by them being that in which the main needles ordinarily would be disposed.

These special needles are disposed in the cylinder at the point where the cylinder-stitch-cam would be at the time the cylinder is raised from lock-stitch position to normal 100 knitting position because it is desired to have no needles under the point of the stitch-cam when the cylinder is moving from this lower position to normal knitting position.

The special needles are restored to yarn-taking position by the usual heel-and-toe-raising-and-lowering cam 24.

What I claim is:

1. A knitting-machine including, in combinative association, a plurality of sets of needles, a longitudinally movable cylinder for mounting at least three of said sets of needles, means for longitudinally moving said cylinder to position it for knitting anti-ravel stitches, a needle-controlling device 110 juxtaposed to said cylinder, and means actuatable by the longitudinal movement of the cylinder for positioning said device in relation to one of the said sets of needles whereby they are thrown out of action.

2. A knitting-machine including, in combinative association, a set of needles having relatively short butts, a set of needle having relatively long butts, and an auxiliary set of needles having relatively longer butts, a cylinder for mounting the several sets of needles, means for actuating the cylinder vertically out of normal knitting position to position for knitting anti-ravel stitches, a needle-controlling device juxtaposed to the cyl- 125 130

inder and movable in relation thereto, and means operated simultaneously with the movement of the cylinder for positioning said device in respect to said auxiliary set of needles, whereby they are thrown out of action preparatory to restoring the cylinder to normal position.

3. A knitting-machine including, in combinative association, a cylinder, a plurality of sets of cylinder-needles mounted therein, an annular member rotatable about the cylinder, a needle-controlling device supported on said annular member and shiftable thereon in relation to a selected set of said needles, means for adjusting the cylinder out of normal knitting position and into position for knitting anti-ravel stitches, means movable with the cylinder in its adjustment for engaging said device to actuate it toward the cylinder, and means operative when the cylinder is being restored to normal position for returning the device to its normal position.

4. A knitting-machine including, in combinative association, a cylinder, means for actuating said cylinder vertically into position for knitting anti-ravel stitches, a plurality of sets of needles mounted in said cylinder, an annular member rotatable about the axis of the cylinder, a cam-carrying bracket pivoted on the member and movable therewith during its rotation, means actuated by the movement of the cylinder for swinging the bracket on its pivot to position it toward the cylinder, independent means for swinging the bracket away from the cylinder, and means for varying the swinging movement of the bracket.

5. A knitting-machine including, in combinative association, a plurality of sets of cylinder-needles, each set having butts of relatively different length, a cylinder for mounting the several sets of needles, means for effecting a vertical movement of the cylinder to position it for knitting anti-ravel stitches, a cam-carrier rotatable about the axis of the cylinder, a cam-carrying element swingingly mounted on the carrier, a resilient instrumentality connected to and influencing the action of the swinging member, and member-operating means juxtaposed to and movable with the cylinder and engageable with the cam-carrying member to swing it toward the cylinder when the latter is in position for knitting anti-ravel stitches, the movement of the cylinder to normal knitting position effecting a releasing of the operating means from the cam-carrying member, whereupon said resilient member becomes active to swing the member away from the cylinder.

6. A knitting-machine including, in combinative association, a plurality of sets of cylinder-needles, each set having butts of relatively different length, a cylinder for mounting the several sets of needles, means for effecting a vertical movement of the

cylinder to position it for knitting anti-ravel stitches, a cylinder cam-carrying member rotatable about the axis of the cylinder, a cam-carrying element swingingly mounted on the member, a resilient instrumentality connected to and influencing the action of the swinging member, member-operating means juxtaposed to and movable with the cylinder and engageable with the cam-carrying member to swing it toward the cylinder when the latter is in position for knitting anti-ravel stitches, the movement of the cylinder to normal knitting position effecting a releasing of the operating means from the cam-carrying member, whereupon said resilient member becomes active to swing the member away from the cylinder, and means adjustable at the will of the operator for varying the extent of movement of the cam-carrying member.

7. A knitting-machine including, in combinative association, a plurality of sets of cylinder-needles, each set having butts of relatively different length, a cylinder for mounting the several sets of needles, means for actuating the cylinder vertically to position it for knitting anti-ravel stitches, a cylinder cam-carrying ring rotatable about the axis of the cylinder, a plurality of needle-operating cams on said ring, one of the cams on the ring being operative to actuate all of the needles of all of the sets another of the cams being operative to actuate selectively only one of the sets of needles, and means juxtaposed to and movable in unison with the cylinder when it is moved into position for knitting anti-ravel stitches for positioning said selectively actuating cam into and out of engaging position with respect to its selected set of needles.

8. A knitting-machine including, in combinative association, a cylinder, means for actuating the same vertically to position it for knitting anti-ravel stitches, a plurality of sets of needles mounted in the cylinder, each set having butts of relatively different length, a cam-carrying ring rotatable about the axis of the cylinder, a stitch-cam mounted on and movable with the ring and operative to act on the needles during the rotation of the ring, a cam-supporting member swingingly mounted on the ring and operative to act on one of said sets of needles, a resilient element connected to the member for actuating it in one direction, and a depending member juxtaposed to, and movable with the vertical movement of the cylinder and engageable with said swinging member to actuate it in the opposite direction and against the action of the resilient element to throw out of action the needles which would be under the point of the stitch-cam when the cylinder is restored to normal knitting position.

9. A knitting-machine including, in com-

binative association, a needle-carrying cylinder, means for actuating the cylinder vertically to position it for knitting anti-ravel stitches, a plurality of sets of needles mounted in the cylinder, each set having butts of relatively different length, a rotatable cam-carrying ring encompassing the cylinder, a stitch-cam operative to engage the butts of all of the needles, a swinging cam-carrying member pivoted on the ring and operative to act on one of said sets of needles, a resilient element connected to the member for actuating it in one direction, a finger-engaging element adjustably mounted on said swinging member, means for securing said element in any of a plurality of adjustable positions, an operating finger juxtaposed to and movable in unison with the cylinder and engageable with said finger-engaging element, and means carried by said swinging member for predetermining the extent of movement thereof in respect to the periphery of the cylinder and whereby the cam on the member may be accurately positioned in respect to the set of needles having the longest butts to engage the same to throw said needles out of action.

10. A knitting-machine including, in combinative association, a needle-carrying cylinder, means for actuating the cylinder vertically to position it for knitting anti-ravel stitches, a plurality of sets of needles mounted on the cylinder, the needles of the respective sets having butts of relatively different length, a cylinder-cam-ring rotatable about the periphery of the cylinder, a sinker-cam-ring associated and movable with the cylinder, a stitch-cam mounted on and movable with the ring for actuating at least two sets of the needles, an auxiliary cam-device also mounted on and movable with the ring and positionable for actuating the set of needles having the longest butts to throw them out of action, said device comprising a bracket swinging on a pivot on the ring, a cam-piece adjustably mounted on the bracket, a spring connected to the bracket for swinging the latter on its pivot away from the cylinder, a headed-element threaded into and adjustable in the bracket, means associated with the headed-element for locking it in any of its plurality of adjustable positions, a stop-element adjustably mounted in the bracket, means for locking the element in any of a plurality of its adjustable positions, and a spring-finger depending from the sinker-cam-ring and engageable with the headed-member to effect inward movement of the same while the cylinder is being actuated to lower it.

11. In a circular knitting machine having a plurality of needles and a cylinder stitch-cam, the combination of means for varying stitch length to produce relatively tight stitches which will not ravel under the normal tension of the take-up and means for selec-

tively throwing out of operation certain needles which in the normal stitch tightening operation would be under the point of said stitch cam and would tend to tear the fabric.

12. A circular knitting machine including a longitudinally movable cylinder, a plurality of sets of cylinder-needles, means for actuating said cylinder to position it for knitting anti-ravel stitches, a cylinder stitch-cam and means controlled by longitudinal movement of the cylinder for selectively throwing out of action certain of said needles which would be under the point of said stitch-cam during the knitting of said anti-ravel stitches.

13. A circular knitting machine including a longitudinally movable cylinder, a plurality of sets of cylinder needles, means for moving said cylinder longitudinally into position for knitting anti-ravel stitches, a cylinder stitch-cam, and means controlled by longitudinal movement of the cylinder to throw out of action certain of the needles which would be under the point of said stitch-cam when the cylinder is restored to normal knitting position.

In testimony whereof I affix my signature.
PATRICK P. LA MONTAGNE.
